UNITED STATES PATENT OFFICE

152,938

DESIGN FOR A PERFUME FLACON

Main R. Bocher, New York, N. Y.

Application January 23, 1948, Serial No. 143,995

Term of patent 14 years

(Cl. D58—8)

To all whom it may concern:

Be it known that I, Main R. Bocher, a citizen of the United States and a resident of the city, county, and State of New York, have invented a new, original, and ornamental Design for a Perfume Flacon, of which the following is a specification, reference being had to the accompanying drawing, forming part thereof.

Fig. 1 is a front elevational view of a perfume flacon showing my new design;

Fig. 2 is a front elevational view on an enlarged scale of the neck end of the flacon, broken away on line 2—2 of Fig. 1; and

Fig. 3 is a top plan view.

I claim:

The ornamental design for a perfume flacon, as shown.

MAIN R. BOCHER.
